[57] CLAIM

The ornamental design for a chimney cleaner, as shown.

DESCRIPTION

FIG. 1 is a rear perspective view, viewed from above, of a chimney cleaner showing my new design;

FIG. 2 is a front elevational view thereof;

FIG. 3 is a side elevational view thereof, viewed from the right of FIG. 2, the opposite side elevation being the mirror image thereof;

FIG. 4 is a rear elevational view thereof; and

FIG. 5 is a bottom plan view thereof.
